KNITTING MACHINE

Stanley R. Shelmine, Wilmington, Del., assignor
to Standard-Trump Bros. Machine Company,
Wilmington, Del., a corporation of Delaware

Application July 18, 1932, Serial No. 623,057

16 Claims. (Cl. 66—134)

This invention relates to a knitting machine and specifically a machine in which patterns are produced by wrapping and a double sole is produced in a stocking by the addition of a yarn 5 in the sole of the foot portion.

It is a broad object of the present invention to provide a machine of novel construction for the knitting of stockings in which the parts are so related that a maximum degree of simplicity 10 is attained even though the machine is capable of producing elaborate results involving wrap designs and a double sole and gusset toe in stockings.

One of the subsidiary objects of the invention 15 is the provision of a machine which may be used either for the production of wrapped designs or the production of plain knitting, the latter being accomplished without any interference from the wrapping instrumentalities. Specifically, so far 20 as this object is concerned the wrapping mechanism is carried by a head which may be moved upwardly away from the needle cylinder either with the latch ring or independently of the latch ring. When it is desired to gain access to the top 25 of the needle cylinder during the knitting of work containing wrapped designs, the wrap finger mechanism and the latch ring may be raised as a unit. On the other hand during adjustment, for example of the yarn fingers, the wrapping 30 mechanism may be raised upwardly while the latch ring remains down in its operative position, it being thus possible to watch the operation without interference by the wrapping elements. Access 35 to the needle cylinder is gained in this case by raising the latch ring only.

It is another object of the invention to provide improved means for guiding and tensioning wrap yarns in their progress from supply bobbins to the laying fingers.

40 A further object of the invention relates to the provision of a compact means for associating elements for transmitting controlling movements from a master cam disc or drum to the elements to be ultimately controlled. This means consists 45 of a series of nested hollow shafts carrying levers acted upon by the cams on the cam drum and also levers which transmit the oscillations of the shafts to the elements which are to be controlled.

Still another object of the invention relates to 50 the provision of improved means for controlling the action of needles to selectively take or fail to take wrap yarns.

It is also the object of the invention to provide an improved arrangement for properly manipulating a double sole yarn, particularly in connec- 55

tion with means which will effect the feeding of main yarns and the changing of such yarns to the needles without interference with the wrapping devices or the yarns trailing therefrom to the needles. In connection with the double sole sole yarn mechanism means are provided for clamping and cutting this yarn, these means being in addition to the clamping and cutting means for the main yarns. There is also provision to insure that the double sole yarn, when it is not 10 to be engaged by the needles, will not interfere with the normal operation of the machine. The last involves the incorporation of means for bringing the double sole yarn away from the needle circle within the normal face of the latch 15 ring and for maintaining it there by the use of proper tension and take-up devices. The clamping and cutting mechanism which is used to clamp and cut the double sole yarn upon each revolution of the needle cylinder is also used 20 to hold the double sole yarn during the knitting of those parts of a stocking in which it is not incorporated.

Other objects of the invention relating more particularly to details of construction, whereby 25 the objects briefly enumerated above are accomplished, will be apparent from the following description read in conjunction with the accompanying drawings in which:

Fig. 1 is a right side elevation of the machine 30 partly in section and with other parts removed for clearness;

Fig. 2 is a front elevation of the machine from which various parts are removed, certain portions thereof being shown in section; 35

Fig. 3 is an enlarged sectional view showing a detail of the wrap yarn tensioning means;

Fig. 4 is a left side elevation of the machine;

Fig. 5 is a horizontal sectional view illustrating more particularly the various parts acting 40 upon the butts of the needles together with other elements located adjacent these;

Fig. 6 is a horizontal section taken on a lower plane and illustrating more particularly elements 45 adapted to act upon needle jacks;

Fig. 7 is an inside elevation of a jack cam;

Fig. 7a is a plan view of the same;

Fig. 8 is a detail showing the means for controlling the stepping of a pattern controlling trick 50 wheel;

Fig. 9 is an enlarged vertical sectional view showing the wrapping mechanism and controlling devices therefor;

Fig. 10 is a horizontal section through the same; 55

Fig. 11 is an elevation of the clamping and cutting mechanism for the double sole yarn;

Fig. 12 is a vertical sectional view showing in inside elevation the relationship of the double sole yarn mechanism to the main yarn feeding devices;

Fig. 13 is a radial vertical sectional view of the same;

Fig. 14 is a perspective view illustrating particularly the means whereby interference between the double sole yarn and the other elements is prevented when the double sole yarn is not being knit;

Fig. 15 is a similar view showing a modified arrangement of the latch ring;

Fig. 16 is a vertical radial section through one side of the needle cylinder showing the relationship between the needles and jacks and mechanism operating thereon;

Fig. 17 is a diagrammatic developed inside elevation of the cams adapted to operate upon the wrap fingers, needles and jacks respectively;

Fig. 18 is a plan view of the device for tensioning and taking up the double sole yarn;

Fig. 19 is a vertical section taken on the plane indicated by 19—19 in Fig. 18; and

Fig. 20 is a diagrammatic view illustrating the relationships of the various controlling cams and also showing the different types of needles associated in the machine, the parts at different levels being shown at different radii.

The machine which is of the rotary needle type comprises an elongated cylinder 2 mounted for rotation about a vertical axis and provided with longitudinally extending slots adapted to slidably receive needles 6 provided with butts 8 of different lengths as will be hereafter pointed out, intermediate jacks 10 provided with butts 12 and lower jacks 14 provided with removable butts 16 and formed at their lower ends with cam engaging ledges 18. The needles and intermediate jacks are designed to slide vertically within the slots, the needles being held in the slots by the use of the usual spring bands, while the intermediate jacks are held therein by engagement with the cylindrical surfaces of certain cams as will be hereafter pointed out. The lower jacks 14 are adapted to slide and also pivot in vertical radial planes about points intermediate their upper and lower ends. To accomplish this the lower jacks have their inner edges formed as shown providing a point 19 about which they may pivot when acted upon by suitable cams in a manner which will be hereafter pointed out. These lower jacks are held in position by a single spring band, which, however, is not relied upon to maintain the jacks in any definite position although as will be obvious from the drawings there will be a tendency for the spring band to maintain the jacks with their lower ends projecting outwardly.

The needle cylinder has secured thereto the usual gear 20 which is driven through an idler by the driving gear 50 controlled by suitable mechanism of the usual type to provide both rotation and reciprocation. The gear 20 is mounted in the portion 22 of the frame.

To provide a support for various elements of the mechanism there is provided a platform 24 which is supported from the lower portion 22 of the frame by suitable posts. A bracket 26 supported by the platform 24 carries a shaft 28 upon which the latch ring supporting bracket 30 is pivoted, this bracket carrying a latch ring 32. The supporting bracket has pivoted to its forward portion a hook 34, engageable with a pin 36 carried by

an upstanding bracket 38 to maintain the latch ring in its lowered position. Manipulation of the hook 34 will release the hook from the pin 36 whereby the latch ring may be raised in the usual manner, a suitable spring being provided to counterbalance its weight and tend to hold it open. The usual cam ring 40 containing the cams for controlling the sinkers is provided, the cam ring having the usual freedom for oscillatory movements limited by engagement of stops with the post 38.

A bracket 42 pivoted on the shaft 28 is provided at its forward end with a downwardly extending portion 44 provided with openings through which project headed screws 46 designed to thread into the latch ring supporting bracket 30. A spring 47 counterbalances the weight of the bracket 42 so that this bracket will tend to remain in the position illustrated in Fig. 1 except when held down by the screws 46. When secured by these screws to the latch ring support, however, the latch ring and the bracket 42 may be raised as a unit by freeing the hook 34 from the pin 36. As will be hereafter pointed out, with the bracket raised and the latch ring alone down in its operative position, plain knitting may be produced whereas when the bracket 42 and the parts which it carries are also down in their operative position wrapping of needles will take place with the formation of designs.

The shaft 43, which carries the gear 50 adapted to drive through an intermediate idler the ring gear 20, projects upwardly and carries at its upper end a gear 52 meshing with a pinion 54, the shaft of which has a universal connection with one element 56 of a split shaft to which element the other element 58 is splined by the use of a key and slot connection. The upper element 58 has a universal connection with the shaft carrying a gear 60 and journaled in the bracket 42. The gear 60 meshes with a gear 62 which is attached to the wrap finger supporting assembly indicated generally at 64.

The assembly 64 includes a plate 66 provided with supporting pins 68 upon which bobbins 70 may be mounted. Above these bobbins 70 there is a plate 74 which forms a sheet for the support of tubes 72, the plate 74 having openings therein through which the tubes extend, being held in position by clamping nuts. As illustrated most clearly in Fig. 3 each of these tubes carries at its outer end a spring tension member 76 the upper arm of which bears against the top of the tube to tension a yarn passing between it and the tube. Extending downwardly through the member 64 are thread guiding tubes 78 which, as illustrated in Fig. 9, project below the assembly to guide yarns to eyes in wrap fingers 80. These wrap fingers 80 are carried by a head forming the lower portion of the assembly and consisting of a preferably single member providing cylinders 82 and 83 having aligned vertical slots therein, there being between these cylinders a groove having a semi-circular radial cross section to receive semi-circular projections 86 of the wrap fingers and thereby provide a pivot for the same. The wrap fingers are held within the slots in 82 and 83 by means of a spring band 88.

The yarns from the bobbins 70 extend upwardly through the openings in the tubes 74 thence under the springs 76 whereby they are tensioned, and then downwardly through the tubes 78 and finally through the eyes of the wrap fingers. The lower ends of the wrap fingers are twisted in the usual fashion so that as the wrap

finger moves outwardly through the needle circle it passes to one side of the needle with which it is to cooperate by reason of the cam action of the hook of the needle on its end, and then 5 on its return passes to the other side of that needle, again due to the camming action of the hook of the needle thereon.

The wrap fingers are provided at their upper ends with butts 98 occupying in the present machine either of two positions, the butts in the upper position being acted upon by cam 92 while those in the lower position are acted upon by cam 94, these cams being pivoted upon a vertical pin 96 and being urged away from the butts of 10 wrap fingers by springs 98, the limiting position being determined by a suitable stop. The different butts 98 on the wrap fingers are provided to 15 secure a possibility of greater pattern variations, since by control of cams 92 and 94 fingers may be selectively rendered active or inactive as desired independently of the selective raising of needles. A greater number of butts with a corresponding number of cams of the type of 92 or 94 may of course be provided as illustrated in my 20 application Serial No. 469,956, filed July 19, 1930.

To control the action of the cams 92 and 94 these cams are provided with projections 100 adapted to be engaged respectively by cam levers 102 and 104 pivoted at 106 and adapted to be 25 acted upon by vertical levers 108 and 110 respectively. Springs 115 tend to hold these levers 102 and 104 in position so that they will act upon the projections 100 to maintain the cams 92 and 94 in condition to act upon the butts 98 and 30 thereby swing the lower ends of the wrap fingers outwardly. Reverse movement of the wrap fingers to carry the lower ends inwardly of the needle circle are effected by the action thereon of the active edge 113 of a cam 112 at points below 35 their pivots 86.

The levers 108 and 110 are pivoted at 111 to the vertical post 107 and are acted upon at their lower ends by levers 114 and 116, the former of which is carried by a vertically extending tube 40 118 journaled in the frame of the machine while the latter is carried by a shaft 120 journaled within the tube 118. The tube 118 at its lower end is provided with a cam following lever 122 arranged to be acted upon by a cam 123 carried 45 by the cam drum 126 while the shaft 120 carries a lever 124 adapted to be acted upon by a cam 125 carried by the same drum. When the levers 122 and 124 are swung outwardly by their respective cams 123 and 125 they cause the levers 108 and 110 to move the levers 102 and 104 against 50 the action of springs 115 and thus cause them to disengage their respective cams 92 and 94. The action of the springs 115 on the other hand will cause the cams 92 and 94 to move inwardly and 55 act upon the butts 98. As will be clear from Fig. 2 the cams 92 and 94 are carried by the bracket 42 so that when the same is lifted they rise therewith.

The bracket 42 is steadied in its active position 60 by engagement of a tapered opening in an extension 130 thereof upon a tapered pin 128 projecting from the upper end of the post 101. A leaf spring 132 carried by the projection 130 is provided with an opening arranged to engage 65 over a pin 134 carried by the post 101 thus forming a releasable latch to hold the bracket in its lowered position prior to the engagement of the screws 46.

Referring now to Fig. 17 the layout of the cams 70 for operating upon the butts of the needles and

jacks will be briefly described. Inasmuch as only one feed point is provided, there is a single set of stitch cams at the feed point. These cams include the upper center cam 136, the lower center cam 138, stitch cams 140 and 142, and end cams 161 and 163, together with the usual cams associated therewith to properly move the needles for the formation of stitches. The cams 140 and 142 are mounted upon slides of the usual type (not shown) so that leveling of the needles may be 10 effected. To provide for the formation of gusset toes, cams 144, 146 and 148 are provided on one side of the feed point while cams 150 and 152 are provided on the other side of the feed point. Cams 144 and 146 are supported together on a 15 single carrying member, cam 144 being adapted to engage long butts only while cam 146 is adapted to engage both medium and long butts of needles as will be later discussed. Between the cams 144 and 146 is a passage 145 for needle butts 20 which is provided for a purpose which will be hereafter made clear. The cam 148 is adapted to raise only long butt needles while it misses short and medium butt needles. These cams are movable in and out in a manner which will be here- 25 after described. The cams 150 and 152 function not only in the production of gussets but also perform the functions of the switch cam or cams usually provided. The end cam 161 is spaced a somewhat unusual distance from the stitch cam 30 148 leaving a space 159 through which the butts move at a low level. This is to accommodate the double sole yarn cutting and clamping mechanism which, when in action, projects over the needle circle.

A lowering picker 154 and raising pickers 156 and 158 all of conventional type are provided.

Below the various cams just described there is a continuous ring of cams 160 which, as illustrated in Fig. 16, serve to hold the intermediate 40 jacks 16 within the slots of the needle circle. The upper surface of the cams forming the ring 160 provide the usual end cams 161 and 163 for the needle butts. There is also provided a cam surface 162 on the lower portion of the ring 160 45 to act upon the butts 12 of the intermediate jacks 16, this cam surface 162 bearing to the other cams the relationship illustrated in Figs. 17 and 20.

The angular relationship between the needle 50 cams and the cams for operating upon the wrap fingers is illustrated in Figs. 17 and 20, the elements 92, 94 and 112 heretofore described having their active portions indicated therein.

A cam 164 is adapted to act upon the shoulders 55 18 of the lower jacks 16. The active surface of the cam 164 is illustrated at 166 which represents the height to which the shoulders 18 are raised thereby. A beveled upper projection 168 on this cam serves to move the lower ends of the 60 lower jacks inwardly thereby releasing the shoulders 18 from the cam after the jacks have been raised to the highest position for cooperation with the wrap fingers. Those jacks which have had their lower ends previously moved inwardly 65 are not engaged by the cams 164, as will be apparent hereafter. The others ride up 218 and then 184 to 166, 212 and 164 being made separate for adjustment purposes as will be later discussed. A safety cam 172 is provided to prevent 70 overrun of those jacks which are depressed by the cam 162, this cam serving to hold the jacks in position for later engagement by the cam 174 which is provided with an independently sloping upper surface 176 designed to engage the shoul- 75

ders 18 and align the jacks so that the butts 16 thereon will cooperate properly with the various fingers 180 and 182.

A safety bevel 170 prevents breaking of butts 5 by cam 218 during reciprocation. A suitable cam, not shown, holds the lower ends of the jacks inwardly until they are rocked by cam 178 which serves to rock the lower ends of the jacks outwardly prior to operation of fingers 180 thereon, 10 (see Fig. 16).

Referring now to Fig. 5 it will be noted that the cams 144 and 146 are carried by a lever 184 pivoted to the frame at 186 and having its inward movement limited by a suitable set screw adapted 15 to engage a fixed part of the machine. The lever 184 carries a pin 183 engaging within a fork formed in a bell crank lever 190 pivoted to the frame at 191. A spring 189 tends to urge the lever 190 in a counterclockwise direction. A link 20 192 connects an arm of the lever 190 with a lever 194 which is carried by one, 196, of a set of hollow nested shafts mounted in vertical bearings and in each other in the frame. The lower end 25 of the shaft 196 carries a lever 198 which is adapted to be acted upon by suitable cams 200 carried by the cam drum 126.

The cam 150, the position of which is most clearly shown in Figs. 17 and 20, is carried by a plunger 202, (Fig. 5), while the cam 152 is similarly carried by a plunger 204. These plungers which are slidable radially in a frame extension and prevented from turning are normally urged outwardly by suitable springs (not shown). Cams 206 and 208 respectively, best shown in 30 Fig. 2, act upon the plungers 202 and 204 to move the same inwardly at proper times. These cams are carried at the upper end of the posts secured to a head 210 normally urged downwardly by a spring 212 to bring an extension 214 which it 35 carries in engagement either with the surface of the main cam disc or in contact with suitable cams 216 thereon. The cams 206 and 208 are vertically adjustable on their supporting posts so that the timing of the cams 150 and 152 in 40 their inward and outward movements may be readily adjusted.

As will be seen from Figs. 7 and 7a, the cam 164 is supported by a block 218 being adjustable relatively thereto by the provision of suitable 45 adjusting screws 220. The block 218 is carried by a slide 222 radially adjustable in the lower bracket of the frame, fixation of the slide in adjusted position being effected by the clamping engagement therewith of a screw passing through 50 an elongated slot in the slide into the bracket.

The cam 178, the active portion of which is indicated in Figs. 17 and 20, is in the form of a lever pivoted upon a fixed vertical post 223. The arm of the lever 178 opposite its active end is 55 adjustably secured by means of a clamping screw 224 to an arm 226 through which is threaded an adjustable set screw 228 designed to bear upon the hub of the lever 178. By reason of the fact that 224 is a clamping screw the lever 226 forms an extension of the lever 228 so that in effect there is a single lever engaged by the link 230. The arrangement just described is for the purpose of providing a relatively fine adjustment of the inward radial position of the active end of 60 the lever 178. By freeing the clamping screw 224 the arm 226 may be pivoted thereabout relatively to the lever 178 until the set screw 228, in properly adjusted position, abuts the hub of 65 178. When such proper position is obtained the clamping screw 224 is tightened. A suitable spring 70

231 urges the lever 178 in a clockwise direction. To oppose this and bring the active end of the lever 178 in position to engage the jacks 14, the link 230 is connected between 226 and the arm 232 carried by one, 234, of the series of nested sleeves previously referred to, the lower end of this sleeve 234 carrying a cam following arm 236 designed to be engaged by cams 238 upon the cam drum 126.

As has been already indicated, there is provided a stack of cam fingers 180 and 182, the lowermost being designated by the last number inasmuch as it has different functions and connections from the others. This finger is connected by a link 248 to an arm 242 of another 15 tubular sleeve of the nest heretofore described which carries at its lower end a cam following lever 244 arranged to be acted upon by a cam 246 on the main cam drum 126.

Springs 248 surrounding an upright fixed shaft 20 have their ends secured to the various cams 180 to the left of their pivot 223, as viewed in Fig. 6, thus normally urging these cams to bring their active ends inwardly for engagement with the butts 16 of the jacks 14. The various cams 180 25 are provided with projections engageable with the butts of tricks carried by a trick wheel 250 which is of conventional type containing tricks provided with butts which may be selectively broken away in accordance with the desired patterning 30 to be obtained. The trick wheel 250 is provided with a series of ratchet teeth 252 which, with one exception, 254, extend radially outwardly to a full extent. The exception, the tooth 254, does not extend outwardly as far as the others for 35 a reason which will be made clear in the description of the operation. Adapted to act upon the ratchet teeth 252 and 254 is a pawl 256 urged inwardly by a suitable spring 257 and carried by a lever 258 connected by a link 260 to the upwardly 40 extending arm of a bell crank 262, the other arm of which is engageable with lugs 264 formed on a pattern chain 266 which is trained about a sprocket 268 moved step by step in the conventional fashion by engagement with a ratchet 45 secured thereto of an oscillating pawl 270 which is adapted to receive one oscillation upon each rotation of the needle cylinder. A guard 272 is pivoted upon the shaft of the trick wheel 250. This guard takes the form of a plate having its 50 outer edge formed in a series of steps 274, 276 and 278. If the step 274 is brought opposite the range of the active end of the pawl 256 then the pawl is free to engage all of the teeth including the tooth 254 so that its reciprocation will 55 impart a step by step movement to the trick wheel. If on the other hand the step 254 is brought opposite the range of movement of the free end of the pawl the pawl is held outwardly so that while it will engage the full size teeth 252 it will fail 60 to engage the shorter tooth 254. Accordingly if this step 276 is brought into cooperation with the ratchet so long as the ratchet is active the trick wheel will be stepped around until the tooth 254 becomes the next one to be engaged by the 65 ratchet. When this occurs the ratchet will reciprocate idly while the trick wheel will rest in fixed position. When the outermost step 278 is brought into engagement with the active end of the pawl 256 none of the teeth is engaged and 70 therefore the pawl will reciprocate idly without producing any movements of the trick wheel.

The guard plate 272 is connected by a link 280 to an idling lever 282 which, in turn, is connected by a link 284 to an arm 286 carried by 75

the outermost of the nested tubular sleeves which carries at its lower end an arm 288 arranged for engagement with a cam 290 properly formed to locate the guard plate 272 in its various required positions.

It will be noted that the projections on the cams 180 which are engaged by the butts on the trick wheel are located to the left of the post 223 as viewed in Fig. 6. Accordingly the presence of a butt in engagement with any of these cams 180 will result in the outward movement of its active end causing it to fail to engage a corresponding butt 16 of a jack 14. It is desired not only to secure such outward movement of the active ends of the fingers 180 by the butts on the trick wheel but also by other means so that a greater variety of patterns may be obtained. To this end there are provided three levers 292, 294 and 296 pivoted vertically above each other upon an upright post and urged in a clockwise direction as viewed in plan by individual springs 298. Each of these levers is provided with a projection of considerable vertical extent designed to engage the tails of a plurality of the cams 180. It may be pointed out that the projection of the lever 296 does not engage the cam 182 although it may engage a plurality of the cams 180 located immediately thereabove. While three of these levers are illustrated, it will be obvious that more or less may be provided as desired.

The levers 292, 294 and 296 are connected by links 300 to arms 302, 304 and 306 respectively, secured to three of the nested shafts forming the group above mentioned. The lower ends of these respective shafts carry arms 308, 310 and 312 engaging cams 314, 316 and 318 carried by the pattern drum 126. By the actuation through the medium of these cams of the various levers 292, 294 and 296, the corresponding groups of various cams 180 may be caused to fail to engage the butts 16 of the jacks 14 irrespective of set-up of the trick wheel 250.

Referring now to Figs. 11 to 15 inclusive the yarn changing and feeding arrangements will be described. The main yarn feeding, cutting and clamping devices which are of a type designed to prevent interference of the main yarns and the cutting and clamping thereof with the wrap yarns are similar to those described and claimed in the application of Harold E. Houseman, Serial No. 529,519, filed April 11, 1931 and will not be herein described in detail except to the extent to which modification is made to secure a proper cooperation with the double sole yarn feeding, clamping and cutting mechanism. Referring more particularly to Fig. 13 it will be noted that two yarn feeding fingers 320 and 322 are provided being pivoted about a pin 334 and arranged to be raised and lowered by devices of the general type disclosed in the Houseman application. The former of the fingers may be provided with a plurality of eyes so that a corresponding plurality of yarns may be fed to the needles in plating relationship. A hook 324 and a presser 326 cooperate to carry the yarns from the fingers initially across the circle of needles so as to be seized thereby at the times when yarn changes take place. A fixed blade 328 operates with a movable blade 330 to cut the main yarn while a clamp 332 in the form of a flexible plate bearing against the movable blade 330 serves to clamp the main yarns after severing takes place coincidently with their removal from action. All of the parts just described are

more thoroughly detailed with respect to their formations, arrangements, and operating connections in the application of Harold E. Houseman just referred to.

Pivoted on the fixed shaft 334 is the double sole yarn feeding finger 336 which is adjacent the main yarn fingers 320 and 322 and is provided with an extension 338 engaged by the upper end of a lever 340 which carries a cam following roller 342 engageable during rotation of the needle cylinder by a cam 344 carried by the rotating sinker dial. The engagement of the roller 342 by the cam 344 serves to raise the finger 336 out of action when those needles which knit the instep are passing the feed point. A suitable spring shown in Fig. 4 at 343 normally urges the double sole yarn finger down into active position.

During the formation of those parts of the stocking which do not involve double sole yarn, it is necessary to keep the double sole yarn finger up in its inactive position irrespective of the continuous rotation of cam 344. For this purpose the inner end of a lever 346 underlies the finger 336, the lever 346 carrying an adjustable abutment screw 348 engaged by the upper end of a plunger 350 which extends downwardly through the frame of the machine as illustrated in Fig. 4 and engages suitable cams on the main cam disc.

Inasmuch as the double sole yarn must be cut and clamped during each revolution of the needle cylinder, it is obvious that the main cutting and clamping mechanism will not suffice for the proper action upon the double sole yarn. Accordingly, a separate cutting and clamping mechanism is provided. This cutting and clamping mechanism is arranged to be movable away from the needle cylinder at proper times to avoid any interference with the stitch formation by the needles. Accordingly a lever 352 is provided pivoted at 354 to the upper bracket and urged by a spring 356 in a counterclockwise direction as viewed in plan. A link 353 connects the lever 352 with an arm 360 carried by the solid innermost shaft 362 of the nested series, which shaft at its lower end is provided with a cam following arm 364 designed to engage a suitable cam 366 on the drum 126. Secured at the inner end of the lever 352 is the bracket 368 on which is pivoted about a horizontal pivot 370 a bell crank 372 carrying at its inner end a cam follower 374 engageable by cams 376 and 378 secured to the sinker dial so as to rotate therewith during rotation of the needle cylinder. An adjustable pad 380 secured in the upper end of the bell crank 372 is arranged to engage means for controlling the clamping and cutting mechanism so that the same is operated upon each revolution of the needle cylinder.

A fixed post 382 carried by the bracket 368 has pivoted thereon a hub 384 of a supporting bracket 386 which is urged by a spring 388 in a counterclockwise direction as viewed in plan to bring an adjustable stop screw 390 carried thereby into engagement with a post 392 secured to 386. The clamping and cutting arrangement which is most clearly illustrated in Figs. 11 and 12 comprises three fixed blades 394, 396 and 398. Between the blades 394 and 396 there is arranged to reciprocate a clamping blade 400 which has an inner end of L-formation so as to hook and engage the double sole yarn feeding from the finger 336. Between the blades 396 and 398 there is a knife blade 402 cooperating with one

of the fixed blades which acts as a ledger blade to sever the yarn. The blade 402 is also of L-formation at its inner end. The blades 400 and 402 which are mounted for sliding movement together are provided with butts 404 at their outer ends engageable within a slot in a slide 406 which is urged outwardly by a spring 408 to bring its outer end 410 into engagement with the pad 380. The spring 408 by moving the blades 400 and 402 outwardly tends to cut and clamp the double sole yarn. On the other hand, inward movement of the pad 380 by reason of action of cams 376 and 378 upon the follower 374 will release the yarn and move the blades to their open positions. As will be pointed out hereafter, one of the movements effected by the cam 376 is an idle one since the double sole yarn is not then engaged by its cutting and clamping elements. The light spring 412 is provided to hold the pad 380 in engagement with the end 410 of the slide to maintain the same under control. This spring, however, is lighter than the spring 408 and does not prevent the spring 408 from urging the slide outwardly.

It is very important that the double sole yarn be so controlled when it is not being knitted that it cannot be engaged by any of the needles. To prevent an accidental engagement of any loose loop thereof by the needles there is provided in the inner face of the latch ring a sloping undercut slot 414 of the type illustrated in Figs. 12, 13 and 14, in which the double sole yarn will lie when the finger 336 is raised out of action and the end of the double sole yarn is clamped in the cutting and clamping means. Instead of providing an undercut such as 414, which is of relatively limited depth, a double sole yarn receiving slot may be provided as illustrated in Fig. 15 at 416 by the use of a separate plate 418 secured to the inner surface of the latch ring inside an undercut portion thereof. This plate is of course designed to form a smooth continuation of the inner surface of the latch ring and in effect forms a part of it. It is made separate only for convenience of construction of the deep slot.

In order to further insure that the double sole yarn cannot throw out a loop engageable by the needles at undesired times, there is provided a tensioning and takeup mechanism of the type illustrated in Figs. 4, 5, 18 and 19. This comprises a lever 420 secured to the shaft 362 which, as previously noted, carries the lever 360 arranged to impart movements to the arm 352. A pin 422 extending upwardly from the arm 420 is arranged to engage the lower portion of a tension disc 424 so as to move the same away from a fixed disc 426 carried by a fixed portion of the frame 428 when the lever 420 rocks in a clockwise direction as viewed in plan. When the pin 422 does not engage the disc 424 this disc is pressed toward the fixed disc 426 by a spiral spring 430 surrounding a horizontally extending post on which is threaded a nut 432 which may be adjusted inwardly and outwardly to regulate the tension on the spring. The double sole yarn passes from the supply through an eye 434, between the discs 424 and 426, thence through an eye 436, an eye 440 carried by the arm 420, and another fixed eye 438, and to the finger 336. The eye 440 moves between the two fixed eyes 436 and 438 to provide a takeup serving to take up slack in the double sole yarn when the arm 420 moves counterclockwise as viewed in plan. By the arrangement just described it will be seen that as the cutting and clamping devices move

outwardly by reason of counterclockwise oscillation of the arm 352 the pin 422 is caused to disengage the disc 424 whereupon the tension of spring 430 comes into action to yieldingly clamp the double sole yarn. At the same time the takeup 440 acts to draw this yarn backwardly through the finger 336 thereby taking the same up and causing it to lie within the receiving slot 414. If the takeup movement is excessive the yarn will be drawn from the supply between the discs 424 and 426, the tension imparted by the spring 430 being relatively light.

The various parts of the machine having been described there will now be taken up the operations involved in the production of a stocking. The needles which have heretofore been designated broadly by the numeral 6 consist of three series arranged as indicated in Fig. 20. The complete set of needles consists of short butt needles 6a, intermediate butt needles 6b, and long butt needles 6c. The short butt needles extend through 180°, while the long and intermediate butt needles form the remainder of the circle being arranged as indicated with a series of intermediate butt needles forming the central portion of the semicircle, which needles are adapted to knit the tip of the toe, sets of long butt needles flanking this central intermediate butt series, which long butt needles are adapted to form the gussets in the toe, and then intermediate butt needles between the gusset needles and the ends of the short butt series. The short butt needles are adapted to knit the front of the leg and top of the foot while the long and intermediate butt series knit the back of the leg, the high splice, heel, sole and toe.

The stocking which the machine is adapted to produce comprises a ribbed top, produced as usual on a rib machine and transferred to the needles of the present machine. Adjacent this ribbed top is an extended top consisting of a plurality of circularly knit courses. Following this is the leg in which patterns are produced in the present machine by wrapping, the patterns extending through the leg, the ankle and the instep and terminating at the rear of the ankle at the top of the heel, the patterns preferably continuing through the high splice, although, if desired they may terminate there. The ankle of the stocking formed on this machine is circularly knit, the high splice being distinguished from the remainder of the ankle by the inclusion of the yarn which has already been referred to as a double sole yarn. A heel is formed by the usual narrowing and widening operation, being, as stated above, formed on the long and intermediate butt needles. The foot of the stocking is formed by rotary knitting in a fashion similar to the formation of the ankle, the bottom of the foot being reinforced by the inclusion of the double sole yarn. At the completion of knitting of the foot, the advanced toe is knit by rotary knitting. The toe which is formed on the long and intermediate butt needles is produced by first narrowing, removing needles successively from action, then inserting all of the long butt needles, knitting a gusset on these needles while continuing the narrowing operation, throwing out of operation all of the long butt needles as a unit, and then widening. The stocking is then finished by the production of the loopers rounds by rotary knitting. Following this, the needles are levelled, the latch ring is lifted, and several turns given to the needle cylinder to press the loops off the needles. One finger, 322, 75

remains in active position at the end of the operation, rising, of course, with the latch ring. The leg and instep portions of the stocking may, if desired, be formed of a plurality of yarns in 5 plated relationship.

When the machine is in its stationary condition the needles are leveled to receive the ribbed top. At this time the yarn fingers 320 and 336 are raised out of action, finger 322 being in action 10 ready to knit the extended top, while cams 149, 142, 144, 146, 148 and 152 are withdrawn from action so that all of the needles form a complete circle at a predetermined level. At this time the cam surface 276 of the guard plate 272 engages 15 the operating extremity of the pawl 256 whereby in spite of any movements of the pawl 256 no rotation will be imparted to the trick wheel 250 since the low tooth 254 will be opposite the pawl having been brought into this position during the 20 finishing of a previously formed stocking. The cams 92 and 94 are withdrawn by the action of the controlling cams on the main cam drum so that they will not engage the wrap fingers thereby avoiding movements of the wrap fingers during 25 the initial formation of the extended top. The upper sole yarn rests within the guarding slot 414, the clamping and cutting mechanism for this yarn being withdrawn by the maintenance of lever 352 in a counterclockwise direction as viewed in plan while at the same time the 30 double sole yarn is prevented from throwing out any loop by the combined action of the tensioning and takeup mechanisms of Figs. 18 and 19.

Following the placing of the ribbed top upon 35 the leveled needles the latch ring and wrap finger head are lowered and the machine set in operation to form the extended top, the needle cylinder rotating counterclockwise as viewed in plan. The extended top is knit from a yarn fed through 40 finger 322, being initially laid across the needles by hand. The cams 140 and 142 are put into action in the usual fashion dropping in against needles of the short butt series so that intermediate butt needles are the first to follow the knitting 45 wave to produce stitches. The remaining parts occupy the positions already indicated. During the knitting of the extended top which consists of a plurality of rounds in the usual fashion, the pawl 256 will reciprocate idly due to the action 50 of the lugs 264 of the pattern chain upon the follower lever 262. Inasmuch as the cams 180 are at this time preferably out of action the various jacks whose lower ends happen to project outwardly will ride up the cam 164 to the wrapping 55 position. No wrapping takes place, however, in view of the fact that the wrap fingers are maintained in their inner position by reason of the inactivity of the cams 92 and 94. Cam 179, which is active only when patterning is being effected, is 60 also out of action. As a result the majority of the lower jacks will remain with their lower ends in inner positions, the spring band being generally not sufficiently strong to move the jacks which fit in the slots with considerable friction. 65 Following the formation of the extended top a yarn change takes place by the replacement of finger 322 by finger 320 which contains one or more yarns of the desired character to form the leg. The cams 92 and 94 for controlling the action 70 of the wrap yarn fingers are now permitted to come selectively into action to act upon the butts of the wrap fingers. The butts are set up in a predetermined fashion to secure the desired patterning in connection with the needle selecting setup. The arrangement of the present machine 75

is such that there may be provided a wrap finger for each needle so that, if desired, all of the needles may be wrapped with the resultant production of quite elaborate designs.

During the formation of the leg the cams 180 which are arranged to operate upon the butts of the lower jacks are permitted to come into action under selective release by the cams 292, 294 and 296. The cams 292, 294 and 296 are selectively under the control of the corresponding cams on 10 the pattern drum so that by several steps of the pattern drum during the formation of the leg, and of course the ankle and foot, control may be obtained from upper, intermediate or lower sets of cams 180 with the result that a longitudinal 15 change of wrap pattern may be produced. For example, two sets of cams 180 may be in operation throughout the formation of the upper part of the leg to produce vertical stripes. If, then, a clock design is to be produced beginning halfway 20 down the leg, one set of cams may be taken out of action and the third set may come into action to control the designing for the formation of such clock. It may be noted that the operation of these cams is in a sense negative, that is, a 25 jack whose lower end is pressed in by a cam 180 will fail to take a wrap yarn inasmuch as it will fail to ride up the cam 166 to receive the yarn from its corresponding yarn finger as the finger is rocked outwardly and then inwardly by the cams 30 92 or 94 and 112. The layout of the trick wheel is of a character to produce patterns in view of this negative type of operation; and it also follows that the more elaborate patterns are produced when less of the cams remain in operation. 35

After wrapping takes place on those needles which are raised by the action of cams 218 and 164 on the lower jacks the lower and intermediate jacks are lowered by cam 163 while the needles 40 are lowered by the upper guard cam to pass through the knitting wave with unwrapped needles.

At the beginning of the formation of the leg the guard plate 272 is moved so that the low portion 45 274 thereof is brought opposite the path of reciprocation of the pawl 256. The pawl is thereby rendered active to step the trick wheel around in the manner determined by the chain 266.

When the position for the beginning of the 50 high splice is reached the drum 126 is given a step to effect various new operations, the needle cylinder still rotating in the same fashion as before. First, it may not be desirable that wrapping should take place through the high 55 splice while on the other hand wrapping must continue through the front of the ankle from the leg into the instep. In such case, those lower jacks 14 which are associated with sole needles (which of course form the high splice) are provided with butts arranged for engagement by the cam 182 which is now brought into action and maintained in action during the formation of the high splice. By reason of this the various sole needles are not raised by the action of cams 218 60 and 164 upon their lower jacks and accordingly they will fail to move upwardly to take yarns from the wrap fingers. The wrap fingers associated with the sole needles continue to move across the needle circle as determined by cams 92 65 and 94, although, if the design is such as not to be detrimentally affected thereby, this may be prevented by the removal of one cam, say 94, from action whereby only the wrap fingers associated with the instep needles are moved in their 70 75

yarn laying paths by the cam which remains in action, the lower butts 80 in such case being omitted from all the fingers associated with sole needles.

5 If wrapping is to take place through the high splice, the cam 182 is kept out of action till knitting of the sole starts. Since formation of the high splice takes place by rotary knitting, wrapping will, in this case, take place as before.

10 The knitting cams retain their previous positions so that the main yarn or yarns are knit in the same fashion as before. Besides these yarns there is now introduced the double sole yarn which will be knit by the sole needles only, being 15 cut and clamped after finishing the feeding of the sole needles upon each revolution of the needle cylinder. To secure an activity of the finger 336 which carries the double sole yarn and which must be moved down into action to cut the double 20 sole yarn into the circle of needles in advance of the first of the sole needles and which must be withdrawn following the passage of the last of the sole needles, the yarn 346 is permitted to drop by the riding of plunger 350 off a cam on the 25 main cam disc which has, up to this point, maintained the lever 346 and the finger 336 raised. The finger 336 is now subject to the action of the follower lever 340 which is rocked upon each revolution of the machine by the cam 344 carried by 30 the sinker dial as illustrated in Fig. 4. This cam is so located that by its action it will raise the finger 336 to prevent feed of the yarn therefrom to the instep needles but will permit the finger 336 to drop at the proper time to cause a feeding 35 of the double sole yarn to the sole needles, the yarn being cut in between the last of the instep needles and the first of the sole needles and being removed after feeding the last of the sole needles and before it has an opportunity to feed the 40 advancing instep needle. Preferably, there is proper provision for cutting and clamping the double sole yarn during such operations. Accordingly the arm 352 which carries the double 45 sole cutting and clamping mechanism is swung clockwise with a simultaneous release of the tension upon the double sole yarn. The timing of the cutting and clamping mechanism is such that immediately after the finger 336 is dropped into action and the first sole needle fed, the clamp 50 will release the end of the double sole yarn so that it may move about with the needle cylinder. As the finger 336 is raised out of action the yarn will be drawn into the jaws of the cutting and clamping mechanism which will be thereupon 55 actuated by the spring 498 following the timed release of the follower 374 by the cam 376 so that the double sole yarn is cut and its end held by the clamping jaws while the raising of the finger 336 draws it into a position above the needles to prevent its seizure by any of the instep needles. The clamping and cutting mechanism 394-492 60 projects across the needles at the position corresponding to 159, Fig. 17. It may be pointed out that while two cams 376 and 378 are provided, 65 these cams in effect act as a single cam, the separation being made only because the timing of the machine is such that the cutting and clamping mechanism is swung inwardly at a time when the space between these cams is opposite the following 374 which could of course not move inwardly if a single continuous cam was provided. The idle movements of the cutting and clamping mechanism resulting from this arrangement produce no result. The yielding mounting of the 70 cutting and clamping mechanism is to prevent 75

damage to the machine in case a high needle should accidentally come along and engage the cutting and clamping devices. The mounting is such that the cutting and clamping devices may swing against the tension of the spring 389 if an accident of this sort should occur. 5

During the formation of the high splice the trick wheel 250 continues to step about in the usual fashion since the pattern is being continued at least through the instep. The double sole yarn 10 does not interfere with wrapping through the high splice if this is desired.

After the completion of the high splice, the double sole yarn feeding finger is rendered inactive by being lifted by lever 346. Simultaneously, 15 the double sole yarn clamp and cutter is withdrawn outwardly by rocking of shaft 352 which simultaneously causes the tension 424 and takeup 440 to become effective to clamp and draw the 20 yarn taut. Since the finger 336 is now fully 25 raised, the yarn is drawn between the retracted clamp and the finger into the slot 414 where it will not be engaged by the needles.

The heel of the stocking is produced by narrowing and widening in the usual fashion, while 25 the sole needles do not knit. Up to the time of the formation of the heel the instep and sole needles, or the instep needles alone, depending on the conditions mentioned above, have been carrying the wrap pattern which is to be continued 30 in the instep after the heel is completed and during the rotary knitting of the foot. In order to insure that the wrap pattern will continue without interruption the guard plate 272 is now moved to bring the high portion 278 into 35 engagement with the pawl 256 preventing it from acting upon any of the ratchet teeth. Accordingly the pawl 256 will reciprocate idly while the trick wheel 250 will maintain its position for the continuation of patterning after the completion 40 of the heel. In order to prevent movements of the wrap fingers both the cams 92 and 94 are now taken out of action. This is necessary inasmuch as the short butt needles are raised to an inactive level during the formation 45 of the heel at which level they would normally be able to receive the wrap yarns. The cams 180 are taken out of action by the elements 292, 294 and 296 and cam 178 is also withdrawn to avoid engagement with the jacks during reciprocation. 50

Upon the last counterclockwise movement of the needle cylinder prior to the first clockwise reciprocation the short butt needles are taken 55 out of action while the long and intermediate butt needles, except for the leading one of the series, remain in position to pass through the knitting wave to take the heel yarn which is lowered into action simultaneously with removal of the leg yarn, the heel yarn in the present machine being the same yarn which is used for the formation of the extended top. To secure the removal of the short butt needles from action the combined cam 144-146 is given an inward movement so that the cam 146 will engage long 60 and intermediate butt needles. The cam 152 is given a full movement inwardly while the cam 150 at the same time moves outwardly. The lowering picker is in an inactive position between the active and inactive levels of the butts. The 65 positioning of the cams as just described results in a depression of the long and intermediate butt needles by the cam 146 following their elevation by the upward projection 161 of the cam ring 160. The long and intermediate butt 70 75

needles are thus lowered to a level below the lowermost extremity of cam 152 and they will accordingly pass upwardly over the cams 142 and 163 and below the center and stitch cams 136 and 140 to form stitches. The short butt needles on the other hand riding over the projection 161 will not be engaged by the cam 146 and will accordingly move on a higher level so as to be engaged by cam 152 whereby they are lifted above all of the cams at the main feed and thereafter during the formation of the heel remain at the inactive upper level. The leading sole needle will fail to pass through the knitting wave upon the initial clockwise movement in the formation of the heel since it will engage the raising picker 158 and be carried thereby to the inactive level. Upon each reciprocation the advancing needles of the sole series will engage a raising picker so that these needles are raised one by one out of action to effect narrowing. Immediately following the counterclockwise reciprocation in which the cam 152 raises the short butt needles, the cam 152 and also the cams 144 and 146 are withdrawn to inactive positions the same as cams 150 and 148. All of the sole needles therefore continue to knit except as they are raised by the picker.

Following the completion of the narrowing operation the lowering picker 154 is brought into action to lower two needles at a time while the raising pickers remain active to raise them one at a time. The widening action for the heel thus takes place, the various other parts maintaining their previous positions.

Rotation of the needle cylinder is now resumed for the knitting of the foot. All of the needles including the instep needles and any sole needles which may remain in raised position are brought down into action by the inward movement of the cam 150. The other parts then take the positions which they had assumed during the formation of the high splice; that is, the plate 272 is moved to bring the low portion 274 opposite the pawl 256 which again becomes active to step the trick wheel around, cam 92 again becomes active to move the wrap fingers associated with instep needles, and the double sole yarn feeding finger and clamping and cutting mechanism again becomes effective to cause the double sole yarn to be knitted by the sole needles, the main yarn being changed to bring the previous leg yarn or yarns into action. Cams 178 and 180 are again rendered active.

Following the completion of the sole the advanced toe is knitted, the extended top yarn again replacing the leg yarn by the lowering of finger 322 and the simultaneous raising of the finger 320. The double sole yarn is withdrawn as before into the slot 414. At this time both cams 92 and 94 are withdrawn from action to stop wrapping. The guard plate 272 is moved to bring the intermediate surface 276 opposite the path of reciprocation of the pawl 256. Accordingly, the trick wheel 250 will continue to step around under the action of the pawl until the low ratchet tooth 254 comes opposite the pawl whereupon the movements of the trick wheel will stop while the pawl will continue to reciprocate idly. This position may not be attained during the knitting of the advanced toe but will be attained sometime prior to the finishing of the stocking so that the trick wheel is brought into proper initial position for the formation of designs in the next stocking to be knit.

Cams 178, 180 and 182 are now again taken out

of action so that the lower jacks do not rise over cams 218 and 264 except accidentally as already indicated.

Following the completion of the advanced toe by a plurality of rounds of rotary knitting narrowing for the toe takes place with the parts assuming the same position as were assumed during the narrowing for the heel. Following the carrying out of the narrowing to such extent that all of the long butt needles as well as the end 10 series of intermediate needles have been removed from action while the central series of intermediate butt needles alone remain knitting the tip of the toe, a movement of the cam disc takes place to initiate the formation of the gusset. 15 The parts in Figs. 17 and 20 are shown in the positions assumed during the bringing of the gusset needles down into action. To obtain the proper positioning of these needles the cam 150 is moved inwardly and then outwardly during the 20 same movement of the main cam drum, the inward movement being of such extent that it will engage only the long butt needles and taking place at the time the central series of intermediate butt needles are passing it. The position 25 of the parts shown in Figs. 17 and 20 correspond to a condition in a counterclockwise reciprocation immediately following this operation. It will be noted that the central series of intermediate butt needles together with the trailing series of long 30 butt needles are passing through the knitting cams, the picker 156 having just lifted to inactive position the last of the leading long butt needles. Before the leading series of long butt needles reach the position of the cam 144 this 35 cam is moved inwardly to such extent that it will engage these leading long butt needles and lower them to a position such that their butts will pass through the opening 145 between the cams 144 and 146. The cam 144 will not engage 40 the short or intermediate butt needles. On the next counterclockwise reciprocation it will be clear that there will remain down in active position all of the long butt needles together with the central series of intermediate butt needles 45 while the short butt needles and the end series of intermediate butt needles will continue to move at the inactive level.

The cams 144 and 146 are again moved outwardly to their previous positions as soon as the 50 gusset needles are lowered, the same being true of the cam 150.

As reciprocation now takes place the gusset will be knit while narrowing continues to remove the gusset needles from action one by one.

Following the completion of the necessary courses to form the gusset, cams 148 and 152 are moved inwardly to a sufficient extent to engage the butts of all of the long butt needles which may remain down in action. Accordingly all of 60 the gusset needles will be raised to the inactive level whereupon the continued motion of the main cam drum will withdraw the cams 148 and 152 from action and the parts will be in those positions which they occupied at the beginning 65 of the widening of the heel. The lowering picker will now be brought into action to lower two needles at a time while the raising pickers continue to raise them one at a time so that widening of the toe will take place.

After the completion of widening the parts are again brought into position for circular knitting, rotation of the needle cylinder being resumed while the stitch cam 150 moves inwardly to bring down all of the needles to knitting positions. The 75

loopers rounds are then knitted using the same main yarn as was previously used for the formation of the extended top, the heel and toe. After the completion of the loopers rounds the needles 5 are levelled by withdrawal of the various cams, the latch ring is raised, and continued revolution causes the loops to be pressed off the needles.

By the provision of the main and double sole 10 yarn feeding mechanisms which have been described, there is avoided any interference between these feeding mechanisms and the wrapping devices which, particularly in the case where each needle is wrapped, form a cage of wrap yarns extending upwardly and inwardly from the needles. Furthermore, by the provision of the double sole 15 yarn receiving slot in the inner face of the latch ring the taking of the double sole yarn at undesired times is prevented.

The above description of the operation has 20 take into account the more elaborate operation involved when wrap yarns are fed to the needles for the production of designs. In the simpler case when no wrap yarns are used and the wrapping head is lifted while the latch ring remains 25 in its lowered position the operation is similar with the exception of those operations involved in the wrapping process. Even throughout a period of knitting, for example, during testing, when no wrapping is taking place the proper angular relationship between the wrap fingers and 30 needles is preserved by the uninterrupted drive through the shaft 56—58.

One feature of the invention to which particular reference may be made is the use of nested 35 levers to provide simplicity of connections between the controlling cam drum and the ultimate parts to be operated. The shafts 118 and 120 form one set of nested shafts while those including shaft 362 form another set, thereby avoiding 40 a multiplicity of levers and link connections.

It will be clear that numerous variations may be made in the details of construction without departing from the spirit of the invention as 45 defined in the following claims.

What I claim and desire to protect by Letters 45 Patent is:

1. A circular knitting machine including a circular series of needles and mechanism cooperating with the needles for the formation of stitches; 50 said mechanism including means for feeding a main yarn to the needles, means for feeding an auxiliary yarn to only certain of the needles, means for clamping the auxiliary yarn, and means other than a clamping or cutting means 55 located outside the needles for receiving the auxiliary yarn at predetermined times to prevent its accidental engagement by needles, said last means consisting of an element provided with a yarn receiving slot located at the level of hooks 60 of needles which are not knitting the auxiliary yarn.

2. A circular knitting machine including a circular series of needles and mechanism cooperating with the needles for the formation of stitches; 65 said mechanism including means for feeding a main yarn to the needles, means for feeding an auxiliary yarn to only certain of the needles during the formation of each of a plurality of courses, and a latch ring, said latch ring being 70 provided with yarn guarding means, wholly outside the needles, behind which the auxiliary yarn is located at predetermined times to prevent its accidental engagement by needles.

3. A circular knitting machine including a circular series of needles and mechanism cooperat- 75

ing with the needles for the formation of stitches; said mechanism including means for feeding a main yarn to the needles, means for feeding an auxiliary yarn to only certain of the needles, and a latch ring, said latch ring being 5 provided with an elongated upwardly extending yarn receiving slot extending across the inner face of the latch ring within which the auxiliary yarn may be located at predetermined times to prevent its accidental engagement by needles. 10

4. A circular knitting machine including a circular series of needles and mechanism cooperating with the needles for the formation of stitches; said mechanism including means for feeding a main yarn to the needles, means for feeding an auxiliary yarn to only certain of the needles, a latch ring provided with a yarn receiving slot, clamping and cutting means for the auxiliary yarn, and means for taking up slack in the auxiliary 15 yarn when held by the clamping means to cause it to engage the slot in the latch ring.

5. A circular knitting machine including a circular series of needles and mechanism cooperating with the needles for the formation of stitches; said mechanism including means for feeding a main yarn to the needles, means for feeding an auxiliary yarn to only certain of the needles, a latch ring provided with a yarn receiving slot, clamping and cutting means for the auxiliary 20 yarn, and means for taking up slack in the auxiliary 25 yarn when held by the clamping means to cause it to enter the slot in the latch ring.

6. A circular knitting machine including a circular series of needles and mechanism cooperating with the needles for the formation of stitches; 30 said mechanism including means for feeding a main yarn to the needles, a movable finger for feeding an auxiliary yarn to only certain of the needles, means for clamping the auxiliary yarn and means other than a clamping or cutting means 35 located wholly outside the needles at the level of hooks of needles which are not knitting the auxiliary yarn for receiving the auxiliary yarn when its finger is moved to an inactive position to prevent its accidental engagement by needles. 45

7. A circular knitting machine including a circular series of needles and mechanism cooperating with the needles for the formation of stitches; said mechanism including means for feeding a main yarn to the needles, a movable finger for feeding an auxiliary yarn to only certain of the needles, clamping and cutting means for the auxiliary 50 yarn, and means other than a clamping or cutting means located outside the needles for receiving the auxiliary yarn when its finger is 55 moved to an inactive position to prevent its accidental engagement by needles, said last means consisting of an element provided with an elongated yarn receiving slot approximately aligned between the clamping and cutting means and the 60 inactive position of the auxiliary yarn feeding finger.

8. A circular knitting machine including a circular series of needles and mechanism cooperating with the needles for the formation of stitches; 65 said mechanism including means for feeding a main yarn to the needles, a movable finger for feeding an auxiliary yarn to only certain of the needles, clamping and cutting means for the auxiliary 70 yarn, means located close to the needles for receiving the auxiliary yarn when its finger is moved to an inactive position to prevent its accidental engagement by needles, said last means consisting of an element provided with an elongated yarn receiving slot approximately aligned 75

between the clamping and cutting means and the inactive position of the auxiliary yarn feeding finger, and means for taking up slack in the auxiliary yarn when held by the clamping means to cause it to enter the slot.

9. A circular knitting machine including a circular series of needles and mechanism cooperating with the needles for the formation of stitches; said mechanism including means for feeding a main yarn to the needles, means for feeding an auxiliary yarn to only certain of the needles, said last means including a finger movable either to an active or inactive position, clamping and cutting means movable either to an active or inactive position simultaneously with the auxiliary yarn finger, and means providing an elongated slot outside the needles for receiving the auxiliary yarn when the finger and clamping and cutting means move to their inactive positions.

10. A circular knitting machine including a circular series of needles and mechanism cooperating with the needles for the formation of stitches; said mechanism including means for feeding a main yarn to the needles, means for feeding an auxiliary yarn to only certain of the needles, said last means including a finger movable either to an active or inactive position, clamping and cutting means movable either to an active or inactive position simultaneously with the auxiliary yarn finger, means providing an elongated slot outside the needles for receiving the auxiliary yarn when the finger and clamping and cutting means move to their inactive positions, and means for taking up the auxiliary yarn to cause it to enter the slot.

11. A circular knitting machine including a circular series of needles and mechanism cooperating with the needles for the formation of stitches; said mechanism including means for feeding a main yarn to the needles, means for feeding an auxiliary yarn to only certain of the needles during the formation of each of a plurality of courses, clamping and cutting means for the main yarn only outside the needles, and clamping and cutting means for the auxiliary yarn outside the needles operative upon the auxiliary yarn during the formation of each of said plurality of courses.

12. A circular knitting machine including a circular series of needles and mechanism cooperating with the needles for the formation of stitches; said mechanism including means for feeding a main yarn to the needles, a latch ring, means for feeding an auxiliary yarn to only certain of the needles during the formation of each of a plurality of courses, said last feeding means being located above the latch ring, means located below the latch ring for holding the auxiliary yarn at predetermined times, and means guarding the auxiliary yarn when so held to prevent its accidental engagement by needles.

13. A circular knitting machine including a circular series of needles and mechanism cooperating with the needles for the formation of stitches; said mechanism including means for

feeding a main yarn to the needles, a latch ring, means for feeding an auxiliary yarn to only certain of the needles during the formation of each of a plurality of courses, said last feeding means being located above the latch ring, means located below the latch ring for holding the auxiliary yarn at predetermined times, and means guarding the auxiliary yarn when so held to prevent its accidental engagement by needles, said last means comprising a member located between the needles and the portion of the auxiliary yarn extending between the holding means and the last feeding means.

14. A circular knitting machine including a circular series of needles and mechanism cooperating with the needles for the formation of stitches; said mechanism including means for feeding a main yarn to the needles, means for feeding an auxiliary yarn to only certain of the needles in the formation of successive courses, means for clamping the auxiliary yarn, and means other than a clamping or cutting means located outside the needles for receiving the auxiliary yarn at predetermined times at the level of hooks of needles which are not knitting it to prevent its accidental engagement by such needles.

15. A circular knitting machine including a circular series of needles and mechanism cooperating with the needles for the formation of stitches; said mechanism including means for feeding a main yarn to the needles, means for feeding an auxiliary yarn to only certain of the needles in the formation of successive courses, means for clamping the auxiliary yarn, means providing a slot at the level of hooks of needles which are not knitting the auxiliary yarn for receiving it at predetermined times to prevent its accidental engagement by such needles, and means for taking up slack in the auxiliary yarn when held by the clamping means to cause it to enter the slot, said last means including a tensioning device between the auxiliary yarn feeding means and the auxiliary yarn supply.

16. A circular knitting machine including a circular series of needles and mechanism cooperating with the needles for the formation of stitches; said mechanism including means for feeding a main yarn to the needles, means for feeding an auxiliary yarn to only certain of the needles in the formation of successive courses, means for clamping the auxiliary yarn, means providing a slot at the level of hooks of needles which are not knitting the auxiliary yarn for receiving it at predetermined times to prevent its accidental engagement by such needles, and means for taking up slack in the auxiliary yarn when held by the clamping means to cause it to enter the slot, said last means including a tensioning device between the auxiliary yarn feeding means and the auxiliary yarn supply, and means for effecting release of the yarn by the tensioning device during knitting thereof.

STANLEY R. SHELMIRE.
